UNITED STATES PATENT OFFICE.

JAMES T. COXEN, OF SIDEBURN, VIRGINIA.

SPRING-MOTOR.

No. 806,644.

Specification of Letters Patent.

Patented Dec. 5, 1905.

Application filed November 3, 1904. Serial No. 231,284.

To all whom it may concern:

Be it known that I, JAMES T. COXEN, a citizen of the United States, residing at Sideburn, in the county of Fairfax and State of Virginia, have invented new and useful Improvements in Spring-Motors, of which the following is a specification.

My invention pertains to spring-motors; and it has for one of its objects to provide a simple, compact, and powerful spring-motor adapted to impart a vibratory motion to devices of various kinds, and more particularly to the spring-supported body of a baby-carriage, the latter with a view of amusing and lulling a baby to sleep.

Another object of the invention is the provision of a spring-motor for the purpose stated embodying an auxiliary spring for actuating a fan or other extraneous device, and a connection intermediate the device that is vibrated and the said auxiliary spring for placing and maintaining the latter under tension while the motor is in operation, and thereby rendering it unnecessary for the operator to wind said auxiliary spring.

Other advantageous features of the invention will be fully understood from the following description and claims when taken in connection with the accompanying drawings, forming part of this specification, in which—

Figure 1 is a side elevation illustrating the motor constituting the present and preferred embodiment of my invention as connected to a spring-supported body to be vibrated. Fig. 2 is an enlarged vertical section of the novel motor *per se*, the pallet-lever of said motor being shown by full lines in its idle position and by dotted lines in its active position. Fig. 3 is a transverse section taken in the plane indicated by the line 3-3 of Fig. 2, and Fig. 4 is a detail section illustrative of the auxiliary spring and the appurtenances thereof. Fig. 5 is a detail view illustrating the relative arrangement of one of the side plates of the main frame, the perimeter of one of the spring-housings, and one of the lateral arms for connecting the latter to the former.

Similar letters designate corresponding parts in all of the views of the drawings, referring to which—

A is a spring-supported device, preferably the spring-supported body of a baby-carriage.

B is my novel motor as a whole, and C is the support on which the motor is mounted.

55 The said support when the motor is used in connection with the spring-supported body of

a baby-carriage may be and preferably is formed by the frame of the carriage.

As best shown in Figs. 2 to 4 of the drawings, the motor comprises a frame having side plates *a*; circular housings *b*, arranged at the outer sides of the said plates and connected thereto through the medium of lateral arms *c*, fixedly connected to the side plates and the perimeters of the housings; a transverse primary shaft *d*, journaled in the side plates and extending into the housings, Fig. 3; spur-gears *e*, fixed on the shaft *d* and interposed between the inner edges of the housings *b* and the outer sides of the frame-plates *a*; a transverse shaft *f*, journaled in the said frame-plates and having pinions *g* intermeshed with the gears *e* and also having, by preference, an angular end *h* to receive a crank or other device for turning the shaft; coiled springs *i*, nested in the housings and connected at one end to the shaft *d* and at their opposite ends to the housings *b*; a ratchet-wheel *j*, fixed, through the medium of a set-screw or other means, on the shaft *d*; a spur-gear *l*, loosely mounted on the shaft *d* alongside the ratchet-wheel *j* and carrying one or a plurality of spring-pressed pawls *m*, arranged to be engaged by the teeth of the ratchet-wheel *j* when said wheel is rotated in the direction opposite to that indicated by arrow in Fig. 2 and to permit the wheel *j* to move independently of the wheel *l* when the wheel *j* is rotated in the direction indicated by arrow; a shaft *n*, connected by one or more gears with the shaft *d*, preferably through the medium of a gear *p* and the before-described gear *l*, and a toothed wheel *q*, fixed on the shaft *n* and forming part of an escapement which I will now describe. In addition to the toothed wheel *q* the said escapement comprises a lever *z*, fulcrumed at *a'* so as to oscillate vertically; a pallet *b'*, arranged on the short arm of the lever and having ends which alternately engage with teeth at opposite sides of a line extending diametrically across the toothed wheel *q*; a shaft *c'*, journaled in the frame; an arm *d'*, fixed on one end of the shaft and having a lateral projection *e'* arranged to be thrown into and out of engagement with the lever *z* after the manner shown by full and dotted lines, respectively, in Fig. 2, and an arm *f'*, fixed on the opposite end of the shaft *c'* and having a projection *g'*, the said projection *g'* being adapted when the lever or arm *f'* is sprung away from an upright *h'* on the frame to be moved across the face of said upright and engaged with the

opposite vertical edges thereof. By reference to Fig. 2 it will be seen that when the projection g' is in the position shown by full lines at one edge of the upright h' the projection e' on the arm d' will bear on the pallet-lever z and lock the same against oscillation or other movement, while when the said lug or projection g' is in the position shown by dotted lines the lug or projection e' will be secured out of engagement with the lever z , so as to leave the latter free to oscillate under the action of the springs i . By springing the lever f laterally away from the upright h' the lug g' may be readily disengaged 15 from either edge of the said upright, and the lever may then be moved from the position shown by full lines in Fig. 2 to that shown by dotted lines, and vice versa.

D is a connection, preferably a link, which 20 is interposed between and connected to the long arm of the lever z and the spring-supported device A. The said connection D is designed when the motor is in operation to rapidly move the device A up and down. 25 This movement of the device A when the said device is the spring-supported body of a baby-carriage will obviously amuse and tend to lull a child in the body to sleep.

r is a transverse shaft journaled in the 30 frame-plates a and bearing a gear-wheel s . t is a ratchet-wheel loosely mounted on said shaft adjacent to one of the frame-plates.

u is a pawl connected to one of the frame-plates and engaging the teeth of the wheel t , 35 so as to hold the latter against retrograde movement.

v is a spring coiled about the shaft r and connected at one end to the wheel t and at its opposite end to the shaft r .

w is a bar pivotally connected to the spring-supported device A and guided by means on one of the frame-plates a .

x is a dog carried by the bar w and arranged to engage the teeth of the wheel t on the downward movement of the bar and to ride idly over said teeth on the upward movement of the bar, and x' is a dog mounted between the frame-plates a and adapted in the position shown by full lines in Fig. 2 to hold the gear 50 s against rotation and in the position shown by dotted lines in said figure to permit rotation of said gear.

Incident to the up-and-down movements of the device A the bar w will be rectilinearly reciprocated, and the dog carried thereby will rotate the ratchet-wheel t step by step, with the result that the spring v will be placed under tension. The gear s is designed to be connected with a fan or other rotary device, 60 (not shown,) and hence it will be observed that when the dog x' is disengaged from the gear s the contracted spring v may be utilized to rotate said rotary fan or device. In virtue of this latter construction it will be observed 65 that the necessity of the operator winding the

spring v at intervals is obviated, which is an important desideratum.

As will be readily appreciated by reference to Fig. 3, the arrangement of the mainsprings i in the housings b and the interposition of the gears e between the inner edges of the housings and the outer sides of the frame-plates a render the construction compact and strong and durable; also, that the shaft f , pinions g , and gears e enable the operator to 75 exert great leverage in winding the shaft d for the purpose of winding or placing the mainsprings under tension.

I have specifically described the construction and relative arrangement of the parts in 80 the present and preferred embodiment of my invention in order to impart a definite understanding of the said embodiment. I do not desire, however, to be understood as confining myself to the said specific construction 85 and relative arrangement of parts, as such changes or modifications may be made in practice as fairly fall within the scope of my invention as claimed.

Having described my invention, what I 90 claim, and desire to secure by Letters Patent, is—

1. In a spring-motor the combination of a suitable frame, a shaft journaled therein, one or more springs for rotating said shaft, an escapement comprising a toothed wheel mounted in the frame, a lever also mounted in the frame, and a pallet carried by the lever and having ends arranged to alternately engage a tooth of the wheel, a driving connection intermediate 95 the spring-actuated shaft and the toothed wheel of the escapement, a bar fixed with respect to the frame, a shaft journaled in the said bar, an arm carried by said shaft and arranged to be moved into and out of engagement with the lever of the escapement, and an arm carried by the shaft and having a projection adapted to be sprung into and out of engagement with the opposite edges of the bar. 100

2. In a motor, the combination with an escapement comprising a toothed wheel, a lever, and a pallet carried by said lever and having ends adapted to alternately engage a tooth of the wheel; of means connected with and adapted to rotate the said toothed wheel, a fixed 115 bar, and a shaft mounted in the bar and having an arm arranged to be sprung into and out of engagement with opposite edges of the bar, and also having an arm for locking the pallet-lever of the escapement against movement 120 when desired.

3. In a spring-motor, the combination of a main frame, housings fixed to the frame at opposite sides of the same and arranged so as to afford spaces between their inner edges and the frame sides, a shaft journaled in the frame, springs disposed in the housings and connected at one end thereto and at their opposite ends to the shaft, spur-gears fixed on the shaft and interposed between the inner edges of the 125 130

5 housings and the frame sides, a shaft journaled in the frame and having pinions intermeshed with the spur-gears, a ratchet-wheel fixed on the shaft connected to the springs, a
10 wheel loosely mounted on said shaft and having one or more pawls arranged to be engaged by the teeth of the ratchet-wheel, an escapement comprising a toothed wheel, a lever, a pallet carried by said lever and having ends arranged to alternately engage a tooth of the wheel, a driving connection intermediate the wheel on the spring-actuated shaft and the toothed wheel, a fixed bar, and a shaft mounted in the bar having an arm arranged to be
15 sprung into and out of engagement with opposite edges of the bar and also having an arm for locking the pallet-lever of the escapement against movement when desired.

4. The combination in a spring-motor, of a
20 main frame, housings fixed to the frame at opposite sides of the same and arranged so as to afford spaces between their inner edges

and the frame sides, a shaft journaled in the frame, springs disposed in the housings and connected at one end thereto and at their opposite ends to the shaft, spur-gears fixed on the shaft and interposed between the inner edges of the housings and the frame sides, a shaft journaled in the frame and having pinions intermeshed with the spur-gears, a 25 ratchet-wheel fixed on the shaft connected to the springs, and a wheel loosely mounted on said shaft and having one or more pawls arranged to be engaged by the teeth of the ratchet-wheel; the said loose wheel being 30 adapted to be connected with a device to be actuated.

In testimony whereof I have hereunto set my hand in presence of two subscribing witnesses.

JAMES T. COXEN.
